DIRIGIBLE HEADLIGHT

Johannes Carel Schulmayer, Bloemendaal,
NetherlandsApplication September 21, 1931, Serial No.
563,931, and in Germany January 24, 1931

7 Claims. (Cl. 240—62)

The invention relates to automobile accessories and particularly pertains to dirigible headlights therefor.

The object of the invention is to provide a simple construction by which the lights will be turned over a larger angle than the wheels, thus lighting the path of travel of the vehicle before the latter has turned the corner, while the swinging movement of the lights may be stopped at a predetermined moment by a mechanism for rendering the swinging mechanism for the headlights inoperative, when it is desired, and a mechanism for automatically uncoupling this mechanism from the steering wheel, when the swinging mechanism meets an obstacle.

The invention is illustrated by way of example in the accompanying drawings, in which

Fig. 1 is a vertical section and elevation of the swinging mechanism to which the lights are applied,

Fig. 2 a plan view of the lower part of the operating mechanism with the upper part removed,

Fig. 2a a plan view of the upper surface of the tappet disc,

Fig. 3 a plan view of the groove and pin mechanism.

Fig. 4 a vertical section of a second form of embodiment.

Fig. 5 a vertical section of the releasing device.

Referring more particularly to the drawings Figs. 1-3, the lower part 1 of a casing is secured, by means of bolts passed through holes 27, to the upper part 2, in which casing the swinging mechanism for the light is contained. The upper part 2 contains two bearings 32 and 31 for a shaft or bolt 3 and the bracket 13 for the headlight, respectively. A crank 4 is releasably connected to the driving shaft 3 in the following manner. The head of the said crank 4 is rotatably and slidably mounted upon the shaft or bolt 3 and maintained upon this shaft by a safety nut 6. This crankhead is provided with a lip 5 adapted to engage a similarly shaped recess 33 of a sleeve 34 forming an integral part of the actuating lever 10.

This sleeve is provided with a recess 35 containing a helical spring 7 bearing with one end upon the bottom of the recess 35 and with the other end against the head 8 of the shaft or bolt 3. This bolt 3 is adapted to slide up and down in the recess 35, the crankhead 4 being disengaged from the sleeve 34 when the crank 4 meets a resistance while the spring 7 is compressed and the lip 5 is disengaged from the recess 33.

The actuating lever 10, as shown in plan in Figs. 2 and 3, is provided with a quadrant arm having a slot 11 in which slot a tappet or pin 12 of a particular elongated shape is slidable. This tappet or pin 12 is eccentrically mounted upon the lower surface of a disc 9 mounted upon or formed integrally with the bracket 13 for turning directly or indirectly one of the head lights or turning indirectly both of the head lights.

This bracket 13 is maintained in the bearing 31 by a sleeve 15 and a nut 14 screwed upon a threaded portion of the bracket 13. The two opposite edges of the slot 11 are parallel and form a guide or cam, within which the tappet or pin 12 moves. The shape of this cam slot 11 is not exactly concentric with the bolt 3, but deviates in accordance with the movement which it is desired to impart to the light. In the middle of the inner cam edge of the slot 11 a recess 16 is provided opposite to a projection or tooth 17 provided in the opposite cam edge of the slot 11.

The recess 16 is so shaped that its parts are concentric with corresponding parts of the tooth 17 and the space between the corresponding parts of the recess 16 and the tooth 17 is so chosen, that the headlight carried by the bracket 13, already has its angle of lead entirely or partly when the tappet 12 leaves the recess 16, whilst the tappet 12 is so shaped in accordance with the space between the recess 16 and tooth 17 that the tappet is rigidly guided in any position, also in the recess 16, and is forced into this recess in order that oscillation of the light on its axis be prevented. In this manner the tappet 12 is forced to communicate a rotating movement to the bracket 13 when the quadrant arm of the lever 10 is actuated by the steering wheel.

By giving the left part of the guiding cam slot 11 a different shape from that of the right one, a different movement and/or degree of rotation can be given to the light in the one direction from that in the other direction. The shape of the cam slot 11 determines the angle over which the lights turn simultaneously with the wheels.

Both parts of the cam slot 11 may have any desired shape in accordance with the movement to be imparted to the lights. Thus a partial angle of lead can be given to the lights by the shape of the cams.

The manner in which the recess fades into the cam slot influences the speed of rotation of the lights and also the time for reaching the required angle of lead.

In order to lock the bracket 13 and also the lights in their normal position, the upper sur-

face of the cam disc 9 is provided with a recess 24 cooperating with a locking pin 25 actuated by a spring 30 and located in a bore of the upper part 2 of the casing. The upper surface of the cam disc 9 is also provided with a groove 23 (Fig. 2a), cooperating with the spring actuated locking pin 25 to act as a brake and steady the movement of the lights.

In the form of embodiment shown in Figs. 4 10 and 5 the quadrant lever 18 rotates in a vertical plane and the part with the slot 11 is of semi-cylindrical shape, at a right angle to the vertical part. Here too the slot 11 is provided with a tooth and a recess.

15 Instead of the forms of embodiment shown and described above, it is also possible to replace the rotatable quadrant lever by a grooved slide. In this case the groove is not circular, but nearly straight in accordance with the degree and speed 20 of rotation to be imparted to the lights.

Fig. 5 shows the device for disengaging the steering wheel mechanism from the driving mechanism for the headlights. The bolt or shaft 3 extends somewhat above the nut 6 and has a central bore in which a link 20 is inserted. This link 20 has a slot 21, which engages a pin 22 passed through the bolt 3. The link 20 is connected by a Bowden cable 36 to a handle near the seat of the driver. By actuating this handle 25 the link pulls up the shaft 3 against the tension of the spring 7 and disengages the lip 5 from the recess 33, thereby disconnecting the crank 4 and associated mechanism from the quadrant lever 10 and its associated mechanism, so that when the 30 crank 4 is driven, its head rotates about the shaft or bolt 3 without driving the quadrant lever.

Instead of providing each light with a mechanism as described, it is also possible to actuate the two lights of the car simultaneously by one 40 mechanism, by providing suitable connections in an obvious manner.

Besides the manually operated means for disengaging the steering wheel mechanism from the driving mechanism, means are also provided for 45 an automatic disengagement in case of an obstruction in the headlight mechanism such as may be caused by rust, dust or other foreign substances between the contacting surfaces of relatively movable parts. This automatic means consists in the arrangement of the lip 5 and the recess 33 which are so shaped that when the bolt 3 is prevented from rotation while the arm 4 is rotated, the lip 5 will move upward out of engagement with the recess 33 and thus allow the 50 steering gear to be operated even if the headlight mechanism should be prevented from operation for any reason whatever.

It will, of course, be understood that the manually operated disengaging means particularly 60 illustrated in Figure 5 is to be operated from the driver's seat.

What I claim is:

1. In a device of the character described, a 65 movable member having a cam aperture formed in its free end, said cam aperture having a recess formed in one of its surfaces and a corresponding projection on its opposite surface, and a pointed-oval shaped tappet adapted to be forcibly moved in predetermined respective positions within said cam aperture, thereby determining the angular positions of a rotatable lamp in respect to its vertical axis, operatively connected with said tappet.

70 75 2. In a device of the character described, a movable member having a cam aperture formed

in its free end, extending thereacross, of differing curvature to the right and left of its center, said cam aperture having a recess formed in one of its surfaces and a corresponding projection on its opposite surface, and a pointed-oval shaped tappet adapted to be forcibly moved in predetermined respective positions within said cam aperture, thereby determining the angular positions of a rotatable lamp in respect to its vertical axis, operatively connected with said tappet. 80

3. In a device of the character described, a movable member having a cam aperture formed in its free end, said cam aperture having a recess formed in one of its surfaces and a corresponding projection on its opposite surface, a pointed-oval shaped tappet adapted to be forcibly moved in predetermined respective positions within said cam aperture, thereby determining the angular positions of a rotatable lamp in respect to its vertical axis, operatively connected with said tappet, and means for operatively connecting said movable member to the steering mechanism of a vehicle. 90

4. Mechanism for actuating dirigible headlights for vehicles adapted to turn on their vertical axis when the vehicle wheels are turned by steering mechanism, comprising, in combination, a standard adapted to support a rotatable lamp, an eccentric disc formed on the lower end of said standard, a pointed-oval shaped tappet formed on the bottom surface of said disc, a movable member having a cam aperture engaging said tappet, and means for operatively connecting said movable member with the steering mechanism of a vehicle in such a manner that the turning of the wheels of said vehicle by said steering mechanism cause said movable member to turn the lamp controlled by said standard to rotate on its vertical axis at a greater angular speed than the wheels of the vehicle. 100

5. Mechanism for actuating dirigible headlights for vehicles adapted to turn on their vertical axis when the vehicle wheels are turned by steering mechanism, comprising, in combination, a standard adapted to support a rotatable lamp, 110 an eccentric disc formed on the lower end of said standard, a pointed-oval shaped tappet formed on the bottom surface of said disc, a movable member having a cam aperture engaging said tappet, means for operatively connecting 115 said movable member with the steering mechanism of a vehicle in such a manner that the turning of the wheels of said vehicle by said steering mechanism cause said movable member to turn the lamp controlled by said standard to rotate on its vertical axis at a greater angular speed than the wheels of the vehicle, and means 120 for readily disconnecting said movable member from the steering mechanism. 125

6. Mechanism for actuating dirigible headlights for vehicles adapted to turn on their vertical axis when the vehicle wheels are turned by steering mechanism, comprising, in combination, a standard adapted to support a rotatable lamp, 130 an eccentric disc formed on the lower end of said standard, a pointed-oval shaped tappet formed on the bottom surface of said disc, means 135 in said disc adapted for frictionally holding said standard to prevent its oscillation on its vertical axis, a movable member having a cam aperture 140 engaging said tappet, and means for operatively connecting said movable member with the steering mechanism of a vehicle in such a manner that the turning of the wheels of said vehicle by 145 said steering mechanism cause said movable member to turn the lamp controlled by said standard to rotate on its vertical axis at a greater angular speed than the wheels of the vehicle, and means 150 for readily disconnecting said movable member from the steering mechanism. 150

member to turn the lamp controlled by said standard to rotate on its vertical axis at a greater angular speed than the wheels of the vehicle.

7. Mechanism for actuating dirigible head-lights for vehicles adapted to turn on their vertical axis when the vehicle wheels are turned by steering mechanism, comprising, in combination, a standard adapted to support a rotatable lamp, an eccentric disc formed on the lower end of said standard, a pointed-oval shaped tappet formed on the bottom surface of said disc, a depression formed in the top surface of said disc adapted to be frictionally engaged by a pin so as

to prevent oscillation of said standard in its various angular positions, a movable member having a cam aperture engaging said tappet, and means for operatively connecting said movable member with the steering mechanism of a vehicle in such a manner that the turning of the wheels of said vehicle by said steering mechanism cause said movable member to turn the lamp controlled by said standard to rotate on its vertical axis at a greater angular speed than the wheels of the vehicle.
